UNITED STATES PATENT OFFICE

JOHN W. FITZ GERALD, OF MILWAUKEE, WISCONSIN, ASSIGNOR TO BRIGGS & STRATTON CORPORATION, OF MILWAUKEE, WISCONSIN, A CORPORATION OF DELAWARE

SWITCH

Application filed March 19, 1931. Serial No. 523,783.

This machine relates to improvements in electrical switches and refers more particularly to a small toggle type switch of the general character illustrated in the copending application Serial No. 420,986, and has as its object to provide a switch of this character which is capable of quick and ready assembly to facilitate its manufacture in quantities.

10 Another object of this invention resides in the provision of an improved switch of the character described wherein movement of the operating member or handle positively moves the movable switch member with respect to the stationary switch contacts to overcome any tendency to retard the action of the movable switch member and insure its movement to open position with a snap action.

20 And a still further object of this invention resides in the provision of an improved switch of the character described in which the movable contactor and its operating mechanism form a unitary structure.

25 With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

35 In the accompanying drawing, I have illustrated one complete example of a physical embodiment of my invention constructed according to the best mode I have so far devised for the practical application of the principles thereof, and in which:

40 Figure 1 is a view partly in transverse section and partly in elevation of a switch structure embodying my invention;

45 Figure 2 is a view partly in longitudinal section and partly in top plan taken through Figure 1 on the plane of the line 2-2; and

50 Figure 3 is a view taken transversely through Figure 1 on the plane of the line 3-3.

Referring now more particularly to the accompanying drawing in which like numerals designate like parts, the numeral 5 represents the body or housing of a switch embodying this invention which is preferably 55 tubular and formed of molded insulating material having its inner end substantially closed by a wall 6 through which a pair of stationary switch members 7 project. The switch members 7 are maintained in spaced 60 relation as they pass through the housing wall 6 by an insert 8 and have outstruck ribs 9 engaging the opposite sides of the wall 6 to retain the members in position. The inner ends of the members 7 are directed angularly to dispose their extreme inner end portions at one side of the longitudinal axis of the housing to form stationary contacts 10 which are adapted to be bridged by a contactor 11 movable therebetween. The outer 65 ends 12 of the members 7 project considerably from the wall 6 and provide terminals to which conductors (not shown) may be connected.

70 The outer end of the housing 5 has an annular flange 13 and the external surface thereof inwardly of the flange is threaded, as at 14, to receive a clamping nut 15 whereby the switch may be secured in an opening 16 in a suitable panel 17. At diametrically opposite sides the housing has flat surfaces 18 adjacent its flange to assure the positioning of the switch on the panel 17 in the desired manner, and preferably so that its operating 75 handle 19, to be later described, is movable in a true vertical or horizontal plane as the case may require. It will be noted that the nut 15 is mounted behind the panel 17 and is therefore concealed to provide a neat external 80 appearance.

85 As stated the stationary switch contacts 10 are spaced apart and the distance therebetween is such as to snugly receive the movable bridging contactor 11. In the present instance, the contactor 11 is formed by a rivet headed at both ends and secured in the outer end of a switch lever 20 of fiber or other insulating material.

90 The switch lever 20 together with the con- 100

tactor 11 carried thereby forms the movable member and is pivotally connected with the actuator or handle member 19 by a pin 23 so that the handle 19 and the movable switch 5 element may be assembled with the housing as a unit.

The handle member 19 may be of any desired configuration and in the present instance is approximately pear or cone shaped 10 with its inner enlarged end forming a truncated sphere of a diameter substantially equal to that of the bore in the housing so that the handle member closes the open end thereof. The innermost end portion of the handle 15 member has a transverse slot or recess 22 extending in a plane substantially at right angles to the axis of the pin 23 to receive the adjacent end of the movable switch lever.

The axis of the pin 23 intersects the longitudinal 20 or major axis of the handle member and the adjacent end of the lever 20 is substantially V shaped, as at 26, to cooperate with a spring urged plunger 27 to yieldably retain the lever 20 in either of two positions 25 with respect to the handle member, as will be later described. The plunger 27 is slidably mounted in an axial bore 21 in the handle member and yieldably urged outwardly of the bore by a spring 28, into 30 engagement with the end of the lever member.

The assembled handle member and movable switch member are mounted in the housing 5 by means of a pair of pintle pins or 35 trunnions 24 passed through aligned openings 25 in the wall of the housing just inwardly of its flange 13 and secured in diametrically opposed openings in the handle member. The axis of the trunnions 24 passes through 40 the center of the sphere shaped inner end portion of the handle member to permit the handle to be swung thereabout while maintaining the open end of the housing closed.

With the handle member and movable 45 switch lever assembled with the housing, the action of the spring 28 yieldably maintains the handle member in a position engaging its medial portion with either the lower portion or upper portion of the peripheral edge 50 of the bore in the housing 5 and the movable switch member inner free end engaging the inner wall of the bore. The handle member and the movable switch member are thus normally maintained in positions with their 55 longitudinal axes forming an obtuse angle, and with the parts in their positions illustrated in Figure 1 the movable switch member 20 is in its contact making position with the contactor 11 bridging the stationary 60 contacts 10.

To disengage the contactor 11 from the contacts, the handle member 19 is moved upwardly. During this upward movement of the actuating member or handle, the pivot 65 pin 23 forming the connection between the

movable switch member 20 and the handle member swings in an arc and moves rearwardly into the housing, and inasmuch as the inner free end of the movable switch member 20 rests on the lower portion of the 70 housing inner wall, such rearward movement on the part of the pivot pin 23 positively moves the movable switch member inwardly as illustrated in dotted lines in Figure 1 so that a positive inward motion is imparted to the contactor to overcome any tendency toward mechanical freezing between the switch contacts and to insure a free and quick opening action as the upward movement of the handle member is continued. 75

As will be apparent the movable switch member 20 remains in its contact making position until the longitudinal axis of the handle member and consequently that of the plunger 27 passes a position axially aligned with the longitudinal axis of the lever 20 at which time the action of the spring 28 quickly snaps the lever 20 to its opposite position. 80

From the foregoing description taken in connection with the accompanying drawing, it will be readily apparent to those skilled in the art to which an invention of this character appertains, that I provide a compact and novel switch construction in which a positive motion is imparted to the movable switch member prior to its spring actuated movement to insure freedom of action and in which manufacture, and particularly assembly of the switch, is greatly facilitated 95 by reason of the fact that the movable elements are assembled with each other prior to being mounted in the housing. 100

I claim:

1. In a switch of the character described, a cylindrical casing having an open outer end, a knob forming a closure for the open end comprising a spherical segment having a diameter substantially equal to the inner diameter of said open end, means mounting the segment for rotational movement on an axis through the center of the sphere, a handle formed on the side of said segment remote from said casing, and being engageable with the edge of said casing to limit the movement of the spherical segment, a switch element pivotally mounted on said segment on the opposite side of the center from said handle, and resilient means mounted in said handle and engaging the segment to effect snap action of said switch. 110

2. In a switch of the character described, a cylindrical casing having an open outer end, a knob forming a closure for the open end comprising, a spherical segment having a diameter substantially equal to the inner diameter of said open end, means mounting said segment for pivotal movement about an axis passing through the center of said sphere, a handle formed on the outer portion of said segment to project from the outer open end 125 130

of the casing and engage the edge of the casing to limit the pivotal movement of the segment, a switch element, means to pivotally mount the switch element from the segment for movement about an axis spaced inwardly from the center of the sphere, whereby the free end portion of the switch element

is positively moved during the pivotal movement of the spherical segment, and a spring disposed within the spherical segment and engageable with the adjacent portion of the switch element to afford a snap action for the switch.

JOHN W. FITZ GERALD.
